SELECTOR MECHANISM FOR MULTISTACK
WEFT REPLENISHING LOOMS

Wilfred C. Howe, Shrewsbury, Mass., assignor to
Crompton & Knowles Loom Works, Worcester,
Mass., a corporation of Massachusetts

Application October 23, 1944, Serial No. 559,937

17 Claims. (Cl. 139—232)

This invention relates to improvements in weft replenishing looms having a pair of stacks of reserve bobbins for each of two shuttles and it is the general object of the invention to provide means for drawing bobbins alternately from either pair of stacks during a succession of replenishing operations involving the shuttle corresponding thereto.

The usual multicolor weft replenishing loom is provided with a magazine having a plurality of stacks of reserve bobbins, generally four stacks for four different colors. Certain fabrics, however, require only two colors and as ordinarily used the magazines of such looms would have only two stacks filled with bobbins, the other two being empty. Mechanism has already been proposed to provide means by which each of two shuttles can be supplied from bobbins drawn from a pair of stacks, but such mechanism has not provided for the alternate drawing of bobbins from any given pair of stacks if the corresponding shuttle remains active for a long time.

In the weaving of certain fabrics, such as blankets, it is customary to weave wide stripes of different colors, each stripe being wide enough to require several transfers of reserve bobbins into the corresponding shuttle. Under such conditions the previously proposed mechanism will ordinarily draw bobbins from one of the stacks of a pair of stacks and then draw the remaining bobbins needed for the weaving of the stripe from the other stack of the pair. The full capacity of the first stack is therefore not utilized and the loom will be stopped by the filling stop motion when the second stack is empty even though bobbins remain in the first stack.

It is an important object of my present invention to assign a pair of stacks to each of two shuttles and provide selector mechanism operating in such manner that bobbins for successive transfers from either pair of stacks will be drawn from alternate stacks of the pair.

Mechanisms of the general character to which my invention relates utilize stops for a stack selector mechanism, one stop for each pair of stacks. These stops assume either of two positions, being either out of the path of the selector in which case the latter registers with one stack of the associated pair, or in the path of the selector to register the latter with the other stack of the associated pair. If a number of successive transfers occur from the same pair of stacks during continued activity of the corresponding shuttle the stop will draw the first bobbin from one of the stacks because it is in the path of the

selector, but the stop is then moved out of the path of the selector and the latter draws the bobbins for the next and succeeding transfer from the other stack of the pair. The first transfer from the other stack releases the stop so that it tries to move into the path of the selector but the stop is prevented from so moving because the selector is in an interfering position. It is for this reason that all but the first bobbin will be drawn from one stack only.

It is another object of my present invention to provide means by which the selector will be moved out of interfering position with respect to both stops on each replenishing operation of the loom so that if the stop of either pair of stacks is free to fall into the path of the selector it will do so.

The type of magazine to which my invention more particularly relates employs a horizontally slideable and vertically rockable selector or color slide which ordinarily has four different operating positions in each of which it registers with a vertical slide or bobbin releaser corresponding to one of the stacks of bobbins. The magazine also employs a transerrer arm which rocks at the time of replenishment to insert the released bobbin into the exhausted shuttle. It is a further object of my present invention to provide mechanism operated by the transerrer arm on each operation thereof to move the selector or color slide to an intermediate position in which it is out of the path of the falling stops. This intermediate position is preferably midway between the extreme positions which the selector can assume when registering with the first and fourth stacks.

The selector ordinarily includes in its construction a sliding rod on which is mounted a casting having a pair of spaced fingers which register one at a time with the various bobbin releasers. It is another object of my present invention to provide a lever pivoted with respect to the magazine and having operative connection with the selector, preferably the rod of the latter. The lever is so constructed that it may assume as many different positions as there are registering positions for the selector, but will have parts thereof in the path of a positioner moving with the transerrer arm so that the lever is moved from any of its several positions to an intermediate position upon each operation of the transerrer arm. In the particular form of the invention illustrated herein the lever is provided with a pair of studs or lugs which are operated upon by a positioning arm secured to the transerrer. These studs or lugs change their positions when

ever the selector is moved, and one or the other of them will always be in position to be engaged by the positioner whenever the transerrer arm operates.

With these and other objects in view which will appear as the description proceeds, my invention resides in the combination and arrangement of parts hereinafter described and set forth.

In the accompanying drawings, wherein a convenient embodiment of my invention is set forth,

Fig. 1 shows a side elevation of a magazine as viewed from the center of the loom and having my invention applied thereto,

Fig. 2 is an enlarged horizontal section on line 2—2, Fig. 1, certain parts being omitted,

Fig. 3 is a front elevation looking in the direction of arrow 3, Fig. 1,

Fig. 4 is a diagrammatic view showing the connection between the shifting shuttle boxes and the stack selector, together with the springs which assist in positioning the selector.

Figs. 5, 6, 7 and 8 are diagrammatic views showing movement of the stack selector from registry with the first, second, third and fourth stacks, respectively, to its mid position,

Fig. 9 is a diagrammatic view showing a fabric which may be woven with my present invention,

Fig. 10 is a diagrammatic view showing a series of successive positions which are assumed by the selector when used with my present invention,

Fig. 11 shows the stops for the selector,

Fig. 12 shows a front elevation of the upper end of one of the bobbin releasers and its hook,

Fig. 13 is a section on line 13—13, Fig. 1,

Fig. 14 is a view similar to a portion of Fig. 1 but showing a modified form of the invention,

Fig. 15 is a front elevation looking in the direction of arrow 15, Fig. 14, and

Fig. 16 is a detailed horizontal section on line 16—16 Fig. 14.

Referring particularly to Fig. 1, I have shown a loom frame 10 on which is mounted a magazine M having four bobbin stacks 11, 12, 13 and 14 reading from front to back of the loom, or right to left. These stacks are associated, respectively, with vertical slides or bobbin releasers 15, 16, 17 and 18 each having upper and lower operating lugs 19 and 20, respectively, for cooperation with the fingers 21 and 22 of a color selector designated generally at 23. The selector includes in its construction a rod 24 slidable in front and back bearings 25 and 26, respectively, carried by the magazine frame, and a casting 27 on which the fingers 21 and 22 are formed.

A bell crank lever 30 is pivoted to the magazine as at 31 and is acted upon by a spring 32 which normally tends to turn the lever in a clockwise direction as viewed in Fig. 1. The lever has operative connection at its upper end with a grooved collar 33 secured to the rear end of rod 24. A connector 35 is attached as at 35' to lever 30 and extends to the opposite side of the loom where it is attached to shuttle boxes or gang GL, see Fig. 4. When the gang GL is down to place shuttle S' in box B' in its active picking position opposite lay L the connector 35 is slackened so that the spring 32 acts to move the selector 23 forwardly or to the right as viewed in Fig. 1. When gang GL shifts upwardly to place box B2 in active position so that shuttle S2 can be picked the connector 35 is tightened and tends to move the selector 23 to its rearmost position. A spring 36 in connector 35 is stronger than spring 32 but yields upon upward shifting of the gang GL if

the selector is prevented by means to be described from moving to its rearmost position.

The upper part of the magazine has pivoted thereto a pair of levers 40 and 41 which correspond respectively to the front pair of stacks 11 and 12 and the rear pair 13 and 14. Each of the releasers 15 to 18 is provided with a hook 42, see Fig. 12 where the hook is shown on releaser 15, for operating the corresponding lever. Thus, when the front releaser 15 is reciprocated vertically its hook passes over the front of lever 40 and rocks the latter around its pivot 43 in a clockwise direction. If, on the other hand, the second releaser 16 reciprocates its hook engages the rear part of lever 40 and rocks the latter in a counter-clockwise direction. In similar manner, the hooks on the rear releasers 17 and 18 act to rock lever 41 in a clockwise and counter-clockwise direction, respectively.

The position of the selector 23 is determined in part by two stops shown in Fig. 11, one for each of the levers 40 and 41. Front stop 45 has its upper end formed with a slot 46 which receives a pin or stud 47 on the forward end of lever 40. The lower end of the stop has a head 48 provided with a short stop 49 and a long stop 50. The stop 50 extends beyond the stop 49 by an amount equal to the shift of the selector 23 from registry with the lugs 19 of bobbin releaser 15 to the lugs of releaser 16. In similar manner, the rear stop 55 has a slot 56 in the upper end thereof to receive a pin 57 on the rear end of lever 41, and the lower end of stop 55 is provided with a head 58 having a short stop 59 and a long stop 60; these latter stops corresponding to releasers 18 and 17, respectively. The long stops 50 and 60 are each movable into and out of the path of movement of the selector 23 as the latter slides horizontally. The stops 49, 50, 60 and 59 correspond to registry of the selector respectively with the releasers 15, 16, 17 and 18.

When lever 40 is in the position shown in Fig. 1 its stop 45 is raised so that the short stop 49 is in position to register the selector with bobbin releaser 15 but when lever 40 rocks in the clockwise direction to its other extreme position due to action of the hook 42 of the releaser 15 incident to a replenishing operation the pin or stud 47 moves downwardly and stop 50 tends by gravity to move into the path of the releaser but will ordinarily be prevented from doing so due to the fact that the selector is in an interfering position due to its registry with releaser 15. Similarly when lever 41 is in the position shown in Fig. 1 the stud 57 is high and holds the stop 55 elevated with the short stop 59 in a position corresponding to registry of the selector 23 with the rearmost bobbin releaser 18, but when lever 41 is rocked in a counter-clockwise direction by the hook 42 of the rearmost releaser 18 the head 58 attempts to move downwardly by gravity to position the stop 60 in the path of the selector for the purpose of registering the latter with the releaser 17, but is prevented from doing so by the selector.

The matter thus far described of itself forms no part of my present invention and may be made as set forth in prior Patent No. 1,030,748 and copending applications Serial Nos. 507,419 filed October 23, 1943, now Patent No. 2,364,978, and 515,203, filed December 22, 1943, now Patent No. 2,363,620.

In carrying my present invention into effect I provide means operative at each replenishing operation of the loom to move the selector 23 to

an intermediate position where it will not interfere with the descent of either of the long stops 50 or 60 into the selector path. Accordingly, I secure to the forward end of the rod 24, the latter for this purpose being somewhat longer than the usual rod, a second collar 65 similar to collar 33 and having groove 66 which receives a lug or stud 67 carried by a lever 68. The latter is pivoted to a stud 69 supported by a plate 70 fixed to the supporting foot 71 of the magazine M.

Magazines of the type set forth herein ordinarily operate with thread cutting mechanism which need not be set forth herein but which include in their construction a supporting casting 72. This casting is ordinarily held by bolts or screws which are tapped into the foot 71 and in order to make my invention readily applicable to existing magazines I utilize the holes which are already tapped in foot 71. Bolts or screws 75 having heads 76 pass through the plate 70 and are then tapped into the foot 71 and pass through the casting 72 to receive nuts 77. When the screws 75 are tight and the nuts 77 tightened the plate 70 is securely held to the foot 71 and stud or pivot 69 is secured in fixed position. Lever 68 is spaced from plate 70 by its hub 78.

The lever 68 has two laterally extending lugs or studs 80 and 81 which are preferably though not necessarily the same distance from the stud 69. The transerrer arm 82 pivoted as at 83 is of usual construction and has on the forward upper end thereof a lug 84 which has been used heretofore to carry a stop screw to limit downward movement of the transerrer arm. I utilize this lug 84 as a mount support means for a positioner designated generally at 85. This positioner has a foot 86 secured by screws or bolts 87 to the lug 84 and transerrer arm and the positioner has an upwardly and normally forwardly extending arm 88 to which is secured a leaf spring 89. The leaf spring may be secured as at 90 to the arm 88 and has its upper and lower ends curved away from the arm 88 as indicated in Fig. 1. The spring 89 and the lugs 80 and 81 are so related that when the arm 88 moves to the left as viewed in Fig. 1 incident to a replenishing operation of the loom the spring will engage first one and then both of said studs 80 and 81 for the purpose of rocking lever 68 around stud 69 to move the selector to an intermediate position out of interfering position with respect to the long stops 50 and 60.

By reason of its connection with the collar 65 lever 68 is free to rock on its pivot 69 as the selector moves backwardly and forwardly and in so moving it changes the position of the studs 80 and 81 with respect to the positioner 85. When the selector registers with the front bobbin releaser 15 the upper stud 80 is in foremost position due to the fact that collar 65 is in its extreme front position and has rocked lever 68 in a clockwise direction as viewed in Fig. 1 to its frontmost position. Stud 81 is in its rearmost position under these conditions. Should a transfer or replenishing operation occur at this time the positioner 85 will move rearwardly or to the left as viewed in Fig. 1, and the upper part of spring 89 will engage the lug 80 and rock the lever 68 in a counter-clockwise direction around its pivot 69 from the full line to the dotted line position of Fig. 5. During this rocking of lever 68 stud 81 due to its forward movement engages the lower end of spring 89, after which the lever 68 will be held in fixed position with the selector 23 in its intermediate or mid-position. The

spring is used for the purpose of absorbing shock but is not essential in all forms of the invention.

If the selector registers with releaser 16 the studs 80 and 81 will be in the position shown in full lines in Fig. 6, and a transfer under these conditions will cause spring 89 again to engage stud 80 first and rock lever 68 to the left to the intermediate position shown in dotted lines. When the selector registers with releaser 17 and

10 a transfer occurs, spring 89 will engage stud 81 and rock lever 68 from the full line to the dotted line position of Fig. 7 to locate the selector in its mid position.

If the selector is in its rearmost position in 15 registry with the bobbin releaser 18 as indicated in full lines in Fig. 8 the bottom stud 81 will again be the first to be engaged by spring 89 during a replenishing operation and the lever 68 will be rocked forwardly or in a clockwise direction around pivot 69 to move the selector to its intermediate position as shown in dotted lines in Fig. 8. In each of these instances spring 89 engages both studs 80 and 81 to position the lever 68, and can yield to prevent breakage, as indicated in Figs. 5 to 8 as the transerrer arm reaches its lowest position.

It will thus be seen that no matter what position the studs or lugs 80 and 81 occupy due to the different positions of the selector 23, operation of 20 the transerrer arm 82 will cause the positioner 85 to move the lever 68 and the selector to an intermediate or mid position in which the selector is out of the path of the long stops 50 and 60 and the latter if free to do so can fall into the 25 path of the selector.

In Figs. 9 and 10 I have indicated diagrammatically how my invention operates in the weaving of a fabric having wide bands of solid color. In Fig. 9 the unshaded areas correspond to white 30 weft woven by shuttle S' which is replenished by white bobbins in stacks 11 and 12, while the shaded areas may be colored, such as blue, and are woven by shuttle S2 replenished by the bobbins in stacks 13 and 14. The bands of these two 35 different colors are each of such width as indicated in Fig. 9 as to require three transfers of their correspondingly colored reserve bobbins while they are being woven.

For the purpose of explaining the operation of 40 my invention it may be assumed that shuttle S2 has concluded the weaving of a wide blue band and shuttle box GL is descending to place shuttle S' in action for the weaving of a white band or stripe. At this time selector 23 is moving 45 to the right as indicated by the arrow shown in position I in Fig. 10. Under these conditions stop 45 may be assumed to be up and when the box GL completes its down shift spring 32 will register the selector 23 with releaser 15 as indicated in position II, Fig. 10. The first transfer 50 in the weaving of the white band, indicated at 90 in Fig. 9, therefore draws a bobbin from the front stack 11 and the stop 48 tends to fall as already described and would be prevented from 55 placing the long stop 50 in the path of the selector except for the fact that the latter is moved to its intermediate non-interfering position indicated in dotted lines, position II. When the selector reaches this intermediate position 60 the long stop 50 falls into the path of the selector and when the latter moves forwardly as the transerrer arm rises it engages long stop 50 and is registered with releaser 16, see position III, Fig. 10. The next transfer indicated at 91, Fig. 65 70 75 9 therefore draws a bobbin from the second

stack 12, and stop 48 is lifted. When the selector moves forwardly from its intermediate position it now registers with the front stack as indicated in position IV, Fig. 10. The third transfer indicated at 92, Fig. 9 therefore involves a bobbin drawn from the front stack and long stop 50 again falls into the path of the selector, and as the latter moves forwardly from its intermediate position it is registered with releaser 16, see position V, Fig. 10. It may be assumed that a small part of the white band remains to be woven during which the selector remains registered with the second stack.

Upon up shift of the shuttle boxes GL to place shuttle S2 in action to weave a blue stripe, connector 35 will be pulled and the selector will move rearwardly. It may be assumed that stop 55 is up with long stop 60 out of the selector path, hence the selector will move to its rearmost position in register with releaser 18, see position VI, Fig. 10. When the first transfer occurs during weaving of the blue band, as indicated at 93, Fig. 9, the selector will move forwardly to its mid-position to permit long stop 60 to fall. This stretches spring 36 after which the selector will be pulled back by spring 36 into register with release 17 as indicated in position VII, Fig. 10. After the next transfer, indicated at 94, Fig. 9, the selector will again be registered with the rearmost releaser 18 as indicated in position VIII, Fig. 10. Subsequent to this last mentioned transfer it may be assumed that only a small part of the blue band remains to be woven during which the selector will again be registered with the third releaser 17 as indicated in position IX, Fig. 10.

Upon the next down shift of boxes GL incident to return of shuttle S' to action to weave another white band, the selector 23 will tend to move to its extreme front position but will be stopped by the long stop 50 to register with releaser 16, since head 48 has remained in the same position that it occupied in position V, Fig. 10. The first transfer during weaving of this second white stripe will result in registry of the selector with releaser 15, after which the sequence of movements of the selector during succeeding transferring operations will proceed as already described.

It will thus be seen that during a plurality of successive transfers involving either color the corresponding bobbins will be drawn alternately from the associated pair of stacks. Although only three transfers have been described in connection with weaving a single band of color, it is apparent from the foregoing description that the alternate drawing of bobbins would proceed after the manner described if more than three replenishments occurred during the weaving of a single band.

It will be understood that when the flat spring 89 is used as a shock absorber it will need to be sufficiently strong to overpower spring 36 in connector 35. When the selector is pulled rearwardly due to upward shift of the shuttle box gang GL spring 36 will stretch if stop 60 registers the selector with releaser 17 of the third stack 13, and the spring 89 must be strong enough to effect a still further stretching of this spring 36 when the gang GL is up and the selector moves to its intermediate position.

In the form of the invention described hereinbefore the actuating lever for the selector has been shown as provided with studs for engagement with the leaf spring 89. Under some conditions it is desirable to be able to effect rela-

tive adjustment between the positioning mechanism and the actuating or placing lever which locates the selector in mid-position at the time of transfer. In order to provide such adjustment I use the modified form of the invention shown in Figs. 14, 15 and 16.

Accordingly, lever 100 similar to lever 68 is provided with a hub 101 and has integral top and bottom lugs 102 and 103, respectively, cast as integral parts of the lever 100 and reinforced by webs 104 shown more particularly in Fig. 16. The lugs extend forwardly from the front edge 105 of lever 100 and are spaced vertically from the hub 101.

The transerrer arm 72 may be constructed as already set forth and carries a positioning mechanism designated generally at 110. The positioning mechanism is secured to the transerrer arm as at 111 in a manner similar to the preferred form of the invention, and is provided with an upwardly projecting arm 112 in which are located two adjustable abutments 113 and 114 for engagement respectively with the lugs 102 and 103. These abutments are similar to each other and each comprises a threaded shank 115 tapped into the arm 112 and held in adjusted longitudinal position by a lock nut 116. The rear part of each abutment, or the right end thereof as viewed in Fig. 14, is provided with a head 117 including in its construction a mass of inherently resilient material 118, such as rubber. This head may be fastened directly to the screw threaded shank 115 by being vulcanized thereto.

The operation of the modified form of the invention is similar to that described in connection with the preferred form of the invention with the exception that a more definite positioning of lever 100 is possible due to adjustment of the abutments 113 and 114 relatively to arm 112. The resilient heads 117 will engage one or the other of the lugs 102 or 103 for the purpose of moving the lever 100 to intermediate position at each operation of the transerrer arm 72 much in the same way as set forth in Figs. 5 to 8. Resilient heads 117 serve as shock absorbers but are sufficiently resistant to compression to overcome spring 36 when the selector is to be moved forwardly from registry with the rear releasers 17 and 18. Adjustment of the abutments relatively to arm 112 facilitates more accurate positioning of the selector in its intermediate position than is possible with leaf spring 89. While I have shown the resilient part of the operating mechanism in this modified form as mounted on the positioning mechanism 110, yet I do not wish necessarily to be limited to this construction, since so far as shock absorbing is concerned it is sufficient if one or the other of the sets of surfaces on lever 100 and arm 112 which engage each other during a transferring operation be provided with a shock absorber.

From the foregoing it will be seen that I have provided a weft replenishing loom operating with two shuttles to each of which is assigned a pair of stacks of reserve bobbins and that means are provided for drawing bobbins alternately from either pair during a succession of three or more replenishing operations occurring during continuing activity of the corresponding shuttle. It will also be seen that the magazine is provided with stops located near the front and back extremes of movement of the selector and that positioning mechanism operates at each replenishing operation to move the selector to a non-interfering position with respect to both of said stops.

so that either of them can fall to stopping position if free to do so. Furthermore, it will be seen that the selector is controlled by a positioning mechanism operated by the transerrer arm for the purpose of moving the selector out of interfering position with respect to the stops. Also, the positioning mechanism includes a lever which is free to move with the selector as the latter is shifted without interference on the part of the arm 85 and spring 89, during non-replenishing periods of operation of the loom. Again, the positioning mechanism serves also as a stop to limit downward movement of the transerrer arm and is preferably provided with a shock absorber which prevents a too abrupt movement of the selector by the transerrer arm. When the shock absorber is used it is sufficiently strong to overpower spring 36 through which is transmitted the force by which the selector is moved rearwardly. It will further be noted that in the modified form of the invention I provide independently adjustable means for engaging the selector positioning lever 100 and that the abutments 113 and 114 are formed with shock absorbing heads for engagement with lugs 102 and 103.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom operating with two alternately active shuttles and having a pair of stacks of reserve bobbins for each shuttle and a bobbin releaser for each stack, a releaser selector movable into register with the releasers one at a time, control means acting to move the selector toward registry with releasers of one pair of stacks when the corresponding shuttle is active and acting to move the selector toward registry with the releasers of the other pair of stacks when the other shuttle is active, a stop for each pair of stacks, each stop capable of assuming two positions in one of which said stop cooperates with said control means to effect registry of the selector with one releaser of the associated pair of stacks, said stop when tending to move to the other position thereof while the selector is registered with said one releaser being prevented by said selector from moving to said other position and said stop when in said other position cooperating with said control means to effect registry of the selector with the other releaser of the associated pair of stacks, and means operated by the loom and effective to move the selector to a position in which said selector is incapable of preventing each of said stops from moving to said other position thereof.

2. In a weft replenishing loom operating with two alternately active shuttles and having a pair of stacks of reserve bobbins for each shuttle and a bobbin releaser for each stack, a releaser selector movable along a given path into registry with all of said releasers one at a time, control means effective during loom operation to move the selector from registry with the releasers of either pair of stacks toward registry with the releasers of the other pair of stacks, a stop for each pair of stacks tending to move into the path of the selector to cooperate with said control means to effect registry of the selector with one of the releasers of the associated pair of stacks but prevented from moving into said path by the selector when the latter has been moved toward the associated pair of stacks by said control means due

to the fact that the selector is in an interfering position, and mechanism operated by the loom and effective to move the selector to a non-interfering position with respect to both of said stops.

- 5 3. In a weft replenishing mechanism having two pairs of bobbin releasers and a selector movable along a given path into registry with all of the releasers one at a time, said selector under one condition of operation of the replenishing mechanism tending to move into registry with one of the releasers of one of said pairs of releasers corresponding to said one condition of operation and said selector tending under another condition of operation of the replenishing operation to move into registry with one of the releasers of the other pair of releasers corresponding to said other condition of operation, a stop for each of said conditions of operation and for the corresponding pair of releasers movable into and out of the path of the selector, each stop when out of the path of the selector permitting the latter to register with said one of the releasers of the associated pair of releasers and when in the path of the selector effecting registry of the latter with 10 the other releaser of the associated pair of releasers, the selector under either condition of operation preventing movement of the corresponding stop into the path of the selector when the latter is registered with said one releaser of 15 the corresponding condition of operation, and means operated by the replenishing mechanism to move said selector to a position where said selector is incapable of preventing movement of either of said stops into said path of the selector.
- 35 4. In a weft replenishing mechanism having two pairs of bobbin releasers and a selector movable along a given path into registry with all of the releasers one at a time, said selector under one condition of operation of the replenishing mechanism tending to move into registry with one of the releasers of one of said pairs of releasers corresponding to said one condition of operation and said selector tending under another condition of operation of the replenishing operation 20 to move into registry with one of the releasers of the other pair of releasers corresponding to said other condition of operation, a stop for each of said conditions of operation and for the corresponding pair of releasers movable into and out of the path of the selector, each stop when out of the path of the selector permitting the latter to register with said one of the releasers of the associated pair of releasers and when in the path of the selector effecting registry of the latter with 25 the other releaser of the associated pair of releasers, the selector under either condition of operation preventing movement of the corresponding stop into the path of the selector when the latter is registered with said one releaser of the corresponding condition of operation, and means operated by the replenishing mechanism to move said selector to a position where said selector is incapable of preventing movement of either of said stops into said path of the selector.
- 40 5. In a weft replenishing mechanism having two pairs of bobbin releasers and a selector movable along a given path into registry with all of the releasers one at a time, said selector under one condition of operation of the replenishing mechanism tending to move into registry with one of the releasers of one of said pairs of releasers corresponding to said one condition of operation and said selector tending under another condition of operation of the replenishing operation 30 to move into registry with one of the releasers of the other pair of releasers corresponding to said other condition of operation, a stop for each of said conditions of operation and for the corresponding pair of releasers movable into and out of the path of the selector, each stop when out of the path of the selector permitting the latter to register with said one of the releasers of the associated pair of releasers and when in the path of the selector effecting registry of the latter with 35 the other releaser of the associated pair of releasers, the selector under either condition of operation when registering with said one releaser of the corresponding pair of releasers being in position to interfere with movement of the corresponding stop into said given path of the selector, and transfer means effective upon each operation thereof to move the selector to a position of non-interference with respect to both of said stops.
- 45 6. In a weft replenishing mechanism having two pairs of bobbin releasers and a selector movable along a given path into registry with all of the releasers one at a time, said selector under one condition of operation of the replenishing mechanism tending to move into registry with one of the releasers of one of said pairs of releasers corresponding to said one condition of operation and said selector tending under another condition of operation of the replenishing operation 40 to move into registry with one of the releasers of the other pair of releasers corresponding to said other condition of operation and said selector tending under another condition of operation of the replenishing operation to move into registry with one of the releasers of the other pair of releasers corre-

sponding to said other condition of operation, a stop for each of said conditions of operation and for the corresponding pair of releasers movable into and out of the path of the selector, each stop when out of the path of the selector permitting the latter to register with said one of the releasers of the associated pair of releasers and when in the path of the selector effecting registry of the latter with the other releaser of the associated pair of releasers, the selector under 10 either condition of operation when registering with said one releaser of the corresponding pair of releasers being in position to interfere with movement of the corresponding stop into said given path of the selector, a transerrer arm and 15 positioning means for said selector caused by operation of said transerrer arm to move the selector to a position on non-interference with respect to both of said stops.

6. In a weft replenishing mechanism having two pairs of bobbin releasers and a selector movable along a given path into registry with all of the releasers one at a time, said selector under one condition of operation of the replenishing mechanism tending to move into registry with one of the releasers of one of said pairs of releasers corresponding to said one condition of operation and said selector tending under another condition of operation of the replenishing operation to move into registry with one of the releasers of the other pair of releasers corresponding to said other condition of operation, a stop for each of said conditions of operation and for the corresponding pair of releasers movable into and out of the path of the selector, each stop when out of the path of the selector permitting the latter to register with said one of the releasers of the associated pair of releasers and when in the path of the selector effecting registry of the latter with the other releaser of the associated pair of releasers, the selector under either condition of operation when registering with said one releaser of the corresponding pair of releasers being in position to interfere with movement of the corresponding stop into said given path of the selector, a transerrer arm, a lever pivoted on the weft replenishing mechanism and operatively connected to the selector and moving with the latter as the selector moves to the different positions thereof in registry with the said releasers, and means operated by the transerrer arm causing said lever to move the selector to a non-interfering position with respect to both of said stops.

7. In a weft replenishing loom operating with two alternately active shuttles and having a pair of stacks of reserve bobbins for each shuttle, each stack having a bobbin releaser and there being a releaser selector movable along a given path into register with all of said releasers one at a time, control means for the selector tending to move the latter first toward the releasers of one pair of stacks and then toward the releasers of the other pair of stacks, a stop for each shuttle and the corresponding pair of stacks movable into and out of said path and when out of said path cooperating with said control means to register the selector with one releaser of the associated pair of stacks and when in said path cooperating with said control means to register the selector with the other releaser of the associated pair of stacks, and means operative during a succession of three or more replenishing operations of the loom during continued activity of either shuttle to move

the associated stop alternately into and out of the path of the selector.

8. In a weft replenishing loom operating with two alternately active shuttles and having a pair of stacks of reserve bobbins for each shuttle, each stack having a bobbin releaser and there being a releaser selector movable along a given path into register with all of said releasers one at a time, control means for the selector tending to move the latter first toward the releasers of one pair of stacks and then toward the releasers of the other pair of stacks, a stop for each pair of stacks movable into and out of said path of the selector and when out of said path cooperating with said control means to register the selector with one of the releasers of the associated pair of releasers and when in the path of the selector cooperating with said control means to register the selector with the other releaser of the associated pair of releasers, transfer mechanism, and means operated by the transfer mechanism in cooperation with the control means and during three or more successive transfer operations during continued operation of either shuttle to effect movement of the stop corresponding to the pair of releasers associated with the shuttle alternately into and out of said path of the selector.

9. In a weft replenishing mechanism including a plurality of bobbin releasers and a selector movable along a given path into registry with said releasers one at a time, the replenishing mechanism including also bobbin transfer mechanism, control means operative under one condition of operation of the replenishing mechanism to move the selector toward an extreme position at one end of said path and operative under a different condition of operation of the replenishing mechanism to move the selector toward another extreme position at the other end of said path, and positioning means operated by the bobbin transfer mechanism to move the selector to a position intermediate the extreme positions thereof.

10. In a weft replenishing mechanism including a plurality of bobbin releasers and a selector movable along a given path into registry with said releasers one at a time, the replenishing mechanism including also bobbin transfer mechanism, control means operative under one condition of operation of the replenishing mechanism to move the selector toward one extreme position thereof at one end of said path and operative under a different condition of operation of replenishing mechanism to move the selector toward another extreme position thereof at the opposite end of said path, a positioning lever operatively connected to the selector, and means operated by the bobbin transfer mechanism causing the lever upon each operation of the transfer mechanism to move said selector to a position intermediate the extreme positions thereof.

11. In a weft replenishing mechanism having two pairs of bobbin releasers, a releaser selector movable into registry with said releasers one at a time, control means tending first to move said selector toward an extreme position in register with a releaser of one of the pairs of releasers and then tending to move the selector in the opposite direction toward another extreme position in register with a releaser of the other pair of releasers, bobbin transfer mechanism, and means operated by the transfer mechanism effective to move said selector to an intermedi-

ate position between said extreme positions thereof.

12. In a weft replenishing mechanism having two pairs of bobbin releasers and a releaser selector tending first to move in one direction toward registry with a releaser of one of said pairs of releasers, and then moving in the opposite direction into registry with a releaser of the other pair of releasers, and means acting upon operation of the replenishing mechanism to move said selector to an intermediate position between said pairs of releasers and out of register with all of said releasers.

13. An operating lever for the bobbin releaser selector of a weft replenishing loom having a transferrer arm provided with a positioner, said lever having provision for pivotal support and having an operating connection for the selector and having spaced means for engagement with the positioner.

14. An operating lever for the bobbin releaser selector of a weft replenishing loom having a transferrer arm provided with a positioner, the selector having a collar thereon, said lever having provision for pivotal support and having a stud for cooperation with the selector collar and having also a pair of studs located on opposite sides of the provision for pivotal support,

said studs being located for engagement with said positioner.

15. A positioner for a bobbin releaser selector operating lever having a pair of spaced studs and adapted for use in a weft replenishing loom having a transferrer arm, said positioner comprising a base for attachment to the transferrer arm and a spring having free ends for engagement with the studs on said operating lever.

16. A positioner for the bobbin releaser selector operating lever of a weft replenishing loom having a transferrer arm, said positioner comprising a base having provision for attachment to the transferrer arm and having a pair of independently adjustable abutments carried by the base for engagement with parts of the operating lever.

17. A positioner for the bobbin releaser selector operating lever of a weft replenishing loom having a transferrer arm, said positioner comprising a base having provision for attachment to the transferrer arm and having a pair of independently adjustable abutments carried by the base for engagement with parts of the operating lever, said abutments including in their construction inherently resilient members for engagement with the operating lever.

WILFRED C. HOWE.
